UNITED STATES PATENT OFFICE.

LESLIE DANA, OF ST. LOUIS, MISSOURI, ASSIGNEE TO THE CHARTER OAK STOVE AND RANGE COMPANY, OF ST. LOUIS, MISSOURI, A CORPORATION OF MISSOURI.

HEATING STOVE.

Original application filed October 29, 1924, Serial No. 746,658. Divided and this application filed June 6, 1925. Serial No. 35,429.

To all whom it may concern:

Be it known that I, LESLIE DANA, a citizen of the United States, residing in St. Louis, State of Missouri, have invented an improvement in Heating Stoves, of which the following description, in connection with the accompanying drawings, is a specification, like characters on the drawings representing like parts.

10 This invention relates to stoves of the type that are supported on legs or base frames, and more particularly to improvements in base frame and leg connections for domestic stoves.

15 The invention aims both to improve the construction of stove legs and the connection of the leg to the stove base and to enhance the general appearance of the stove. The invention further aims to economize in 20 the time and cost of production of the parts, and to increase the strength and rigidity of the assembled stove.

25 Further aims and advantages of the invention appear in connection with the description of the construction shown in the accompanying drawing, illustrating one embodiment of my invention; wherein—

Fig. 1 is a half front elevation and half cross section of the lower part of a stove, 30 showing the details of construction of the legs and base;

Fig. 2 is a similar half side view and half cross section; and

Fig. 3 is a detail view of the improved 25 manner of attaching the legs to the base.

The present application is a division of my application for heating stoves, filed October 29, 1924, Serial No. 746,658, and although the embodiment of the invention 40 shown in the drawings illustrates the invention associated with elements of a heating stove of the hot air type, it is to be distinctly understood that my invention is not restricted to use with stoves of that type 45 but is capable and intended for use on stoves of any other type.

My invention is particularly useful in connection with heating stoves and ranges 50 which are metal plated, enameled or otherwise finished to produce a highly ornamental and pleasing appearance. More particularly my invention aims to improve the appearance of the stove at the point of connection 55 of the legs to the base.

Heretofore in the construction of plated and enameled stoves, it has been customary to enamel the lower edge of the base, jacket or other part which is supported by the legs and is subject to view. It is difficult to enamel the lower bottom edge of such parts and even when properly enameled, the coating or finish is very liable to become damaged during packing and shipment, resulting in an unsightly connection at that point when the stove is assembled for use.

In the embodiment shown in the drawings my invention is shown applied to a stove including a bottom pan 10 of the ash pit 11. As shown, the bottom pan 10 is dished and formed with a horizontal flange 12 on the four sides thereof, the outer edges of which are formed with short perpendicular flanges 13 extending above and below the plane of the flange 12. When the invention is applied to a heating stove of the type illustrated in the parent application above referred to, the lower edges of the side jacket J are held and confined within the upwardly extending portions of the flanges 13.

According to my invention the supporting 80 legs 14 may be of any desired shape or design, and are preferably provided with a horizontal lug or ear 15, upon which the bottom pan, base, or other part rests at its four corners only. Although my invention 85 is advantageous and desirable in connection with stoves having rectangular or polygonal bases, the invention is also adaptable to bases of other shapes. The legs may be secured to the bottom pan, base or other part in any 90 approved manner, as by bolts.

The legs are formed with an upwardly extending lap or skirt 16 which overlaps and covers the lower edge of the pan, base or other part supported by it. The usual base 95 skirting 17 is suitably secured to the legs, and is preferably formed with a similar lap or skirt 18 to cover and conceal the lower edge of the pan, base or similar part.

In the manufacture of stoves embodying 100 the approved construction, the several parts are cast in the usual form and the desired parts are enameled, plated or otherwise suitably finished. The parts are then packed ready for shipment.

105 In assembling the parts of the stove, it is not important whether the lower bottom edges of the base, jacket or other outside

part to be supported by the base, are properly coated or finished, as this edge will be adequately covered and concealed by the laps or skirts of my leg and base skirting.

5 Advantages of my invention are in the economies of molding, finishing, packing and sand blasting as well as in enhancing the general appearance of the assembled stove.

10 My invention is not restricted to the details of construction shown and described.

I claim—

1. In a stove, an ash pit and pan, a jacket surrounding said ash pit, and supported by the pan, and legs for supporting the stove 15 above the floor and engaging the pan only at the corners, said legs having an upper skirting to overlap and cover the edge of the ash pit and the lower edge of the jacket.

2. In a stove, a heating unit including an 20 ash pit having a substantially rectangular bottom pan, a jacket surrounding said heating unit and supported upon said bottom pan, legs supporting the stove above the floor and supporting the ash pan only at the 25 corners thereof, an upwardly projecting skirt formed on said legs to overlap and cover the exposed edge of the bottom pan and lower edge of the jacket, and means connected to said legs and extending therebetween to overlap and cover the side edges of the bottom pan and bottom edge of the jacket.

3. In a stove, a heating unit, a surrounding jacket therefor, a stove bottom and legs 30 having a connecting skirting and stove bottom engaging portions for supporting the

stove including inwardly extending flanges engaging the stove bottom at spaced points for supporting purposes and upwardly extending continuous flanges for covering the 40 lower edge of the jacket.

4. A supporting leg for stoves and the like for protecting from view the uncoated bottom edges of a heating unit having an exterior jacket, said leg being of suitable shape 45 and coated or otherwise suitably finished on its outer face to present a pleasing appearance, an inwardly extending shelf near the upper end of said leg for supporting the stove, and an upwardly extending marginal skirting extending above the plane of the shelf and above the bottom unfinished edges of the heating unit and jacket.

5. In a stove, an outer casing, a bottom pan, and a supporting frame comprising 55 spaced legs and connecting skirt members with their top edges coextensive, each leg having an inwardly extending bracket or shelf portion spaced below its top edge forming a supporting ledge for the outer 60 edge of said bottom pan, and said outer casing having an inwardly and downwardly extending lower edge adapted to extend behind the top edges of said legs and skirt members and rest upon the outer edge of 65 said bottom pan, whereby the lower edge of said casing is concealed by the top edges of said legs and skirt members.

In testimony whereof, I have signed my name to this specification.

LESLIE DANA.
